UNITED STATES PATENT OFFICE.

WILLIAM F. MOWRY, OF WALLINGFORD, CONNECTICUT, ASSIGNOR TO INTERNATIONAL SILVER COMPANY, OF MERIDEN, CONNECTICUT, A CORPORATION OF CONNECTICUT.

DESIGN FOR A SPOON OR SIMILAR ARTICLE.

Application filed May 29, 1922. Serial No. 2,455. Term of patent 7 years.

To all whom it may concern:

Be it known that I, WILLIAM F. MOWRY, my new design; and a citizen of the United States, residing at Wallingford, county of New Haven, and State of Connecticut, have invented a new, original, and ornamental Design for a Spoon or Similar Article, of which the following is a specification, reference being had to the accompanying drawing, forming a part thereof.

Fig. 1 is a front view of a handle showing Fig. 2 is a side view thereof.

I claim: The ornamental design for a spoon or similar article as shown.

WM. F. MOWRY.
